UNITED STATES PATENT OFFICE

JOSHUA PEVSNER, OF BROOKLYN, NEW YORK

DECORATED TRANSPARENT CONTAINER

Application filed March 12, 1930. Serial No. 435,146.

This invention relates to a method of decorating transparent containers, such as bottles of any shape and form which may be used for many decorative purposes such as 5 lamp stands or merely as an ornament in itself. My invention also includes the decorated container as the product of the process.

The object of my invention is to produce 10 a decorative and artistic article which may be used for a great many purposes such as pure ornamentation or lamp bases as enumerated above or any other use to which such article is adapted. Decorative columns 15 may be produced in the same manner and the object is not limited to bottle formed containers.

Another object of my invention is to devise a process to produce the decorative 20 article.

A third object consists of the development of effective and efficient tools whereby any form or shape or figure or configuration may be produced within the container.

25 The accompanying drawings illustrate by way of example, a decorated transparent container, and the various tools required to produce the decorations and the manner in which they are produced.

30 Figure 1 shows a decorated bottle.

Figure 2 shows a funnel used in the decorating process.

Figure 3 shows a tool for manipulating the colored decorative material.

35 Figure 4 is an enlarged fragmentary section showing the manner in which the funnel is used.

Figure 5 shows an enlarged fragmentary section of the decorated container wall.

40 In accordance with my invention I preferably use a transparent or translucent container of glass or other material which may be of any shape whatever and may have indentations or other configurations in the wall 45 surface of the container as desired. The container may be a narrow neck bottle or a large open mouth bottle of a circular, oval, square or any other shape.

Colored granular material is poured into 50 the container to form the various designs

and configurations of the decoration. The colored material which I have found preferably is fine grain sand which has been previously colored with water colors or some other coloring matter. The natural color 55 of sand itself or of colored stone crushed and ground to the desired granular size or any other material may be used to secure the various colors. The sand may be of any degree of fineness but the best results are 60 secured if a fine textured sand is used, since fine grained sand flows more easily and affords a more finished appearance to the decoration.

The manner in which the container is 65 decorated will now be described. A funnel 2 having a long tube 3 extending therefrom, has the lower end 4 bent so that the open end of the tube projects substantially in a horizontal direction and extends some distance from the axis of the tube. Funnels of various sizes may be used and which have varying tube openings in order to assist in controlling the quantity of colored sand which pours from the funnel. The 70 funnel is inserted within the neck of the bottle and a small center mound 5 of sand is poured. This may be distributed to form a uniform unbroken and level line around the bottle shown by the short sections 6 of 75 straight line top surface in Figure 1. This line may remain as a level straight line or it may be altered to take any form. The manner in which this uniform line is broken to form the downwardly extending 80 points 24 will be described presently.

Many of the decorative forms or configurations are secured with the funnel only, such as the wave form of decoration shown by the layer 7. This form is secured by 85 disposing the nozzle of the bent tube 4 of the funnel at the center over and in fact, if desired, the mound 5 and sand of a different color from that forming the first layer, is poured into the funnel and the tube 90 is brought radially to the container wall but should not contact therewith. The sand pours from the nozzle until a mound is formed, the apex of which is approximately 95 level with the nozzle. The dry grains of 100

sand naturally assume the conical shaped mound 7. When this mound is built up as high as desired, the nozzle is removed to the center of the container and then brought radially to the container wall at a short distance from the first conical mound 7. A second conical mound 8 is here formed, and when it is built up to the desired height which may be on a level with that of mound 7 or at a greater or lesser height, the nozzle is again withdrawn radially to the center and brought radially to the container wall a short distance from conical mound 8 and a third mound 9 is formed. This process may continue around the bottle forming a series of conical mounds which appear from the exterior of the container as a series of cones of which 7, 8 and 9 are a part.

With this second layer of colored sand above the first or lower layer, a forming tool 10, such as that shown in Figure 3 and having a flattened end 11, is pressed down through the upper layer of sand and into the lower layer. The outer edge of the flattened end 11 of the forming tool is in contact with the inner wall of the container so that the sand in the lower layer is pushed aside and the sand of the upper layer follows the depression made by the end of the tool and remains in this depression. This operation is shown in enlarged form in Figure 5 where the end 11 of the tool 10 has been pushed down into the layer 12 forming a depression therein similar to the depression 13. The edges of the depression may be rounded as shown by the curved depression 13 or the edges may be sharp as shown by the depressions 24 of Figure 1. As the tool is withdrawn the sand in layer 14 above drops into this depression and remains there forming a second depression identical to that shown at 13. This operation may be continued and any number of the depressions made at uniform distances apart forming a regular succession of round lumps in the layer 12 or to express it in another manner, a series of pointed projections 13 extending downwardly from the layer 14. This tool may also be used to round off any of the mounds in any desired form such as that shown in layer 15 where the peaks 16 of the mound are rounded off and the depressions 17 are filled in to form a uniform wavy contour. Similarly the contour of layer 18 may also be formed. It will be understood that the particular contours of the upper edge of layers 17 and 18 which have no sharp contours such as found with the depression 13 are formed preferably before the next succeeding layer of sand is poured on top.

Another manner in which the sand may be used to form a decorative scheme of somewhat different form is shown in Figure 1. In this type of decoration a series of mounds

19 are formed which may be all of one color or may be of different colors and between the sloping sides of successive mounds a second mound 20 is formed of a different color. This form of decoration may be altered with the tool in any desired manner or may be left as a series of mounds just as it is poured from the funnel as shown by the typical decorative scheme illustrated by mounds 19 and 20.

By careful manipulation of the tool 10 various designs may be formed of known figures. The camel 21 illustrates this form of decoration and it is produced in the following manner. A mound of sand is formed upon a layer 22 of any desired color, the apex of which mound forms the top of the body proper of the camel 21. With the aid of the tool 10, legs are formed by pushing aside the sand of the lower layers and permitting the sand forming the body of the camel to flow into the depressions formed in the lower layers. The body proper of the camel may also be manipulated with the tool to develop the desired form. A second small mound is then poured to form the head 23. This sand in turn is manipulated by the tool to form the long neck surmounted by the head of the camel. Similarly the sand may be manipulated to form figures of any desired animal or any desired figure in the same manner that the camel was developed.

I do not desire to limit myself to the specific type of funnel or even to limit myself to a funnel inasmuch as any device capable of pouring sand adjacent the inner wall of the transparent container is suitable to the purposes of my invention. In containers having no neck or having large mouthed openings a trough may be sufficient. Similarly various forms of tools may be devised to aid in forming the various configurations and shapes desired. The tool shown in Figure 3 is a tool of general application and tools having special forms for special purposes may be devised to secure practically any result in the manipulation of the sand.

What I claim is:

1. A method of decorating transparent containers comprising pouring sand against the wall of the container from the spout of a funnel, withdrawing the spout of the funnel to the center of the container, carrying the spout adjacent the container wall at a predetermined distance from the preceding pouring position and pouring sand of the same or different color at this position, continuing the pouring in this manner completely around the container wall and repeating the process on top of the preceding pouring with sand of a selected color or colors, and shifting the sand in the lower

layers in any desired manner to secure any desired design.

2. A method of producing upon a transparent surface a decorative design in granular or powdered material containing portions of different colors comprising depositing material of one color against the transparent surface and material of another color above the first material and against the transparent surface and causing portions from the upper material of a color to occupy areas upon the transparent surface occupied by material of the other color by causing the displacement of the lower material adjacent the upper material and extending the displacement upon the transparent surface to conform to the figure or design desired whereby gravity forces the upper material into the displaced area to form the design or figure in the second material.

3. A method of producing upon a transparent surface a decorative design in free flowing granular or powdered material containing portions of different colors comprising depositing material of one color against the transparent surface, then depositing material of another color above and upon the first material and against the transparent surface, displacing portions of the first material at the point where the two materials contact with each other at the transparent surface thereby causing portions of one material to occupy areas against the transparent surface which were occupied by the material of the other color and the displaced material being held in place by the other material, and extending the displacement of the first material against the transparent surface to conform to the desired figure or design.

In testimony whereof I affix my signature.
JOSHUA PEVSNER.
